ABSTRACT

Murine monoclonal antibodies directed against a novel outer membrane protein (OMP) of *Haemophilus influenzae* have been isolated and characterized. The gene encoding of the outer membrane protein has also been isolated and characterized. Portions of the DNA sequence of the 15 kD OMP gene are useful as probes to diagnose the presence of *Haemophilus influenzae* in samples. These DNA's also make available polypeptide sequences of immunoreactive epitopes encoded within the gene, thus permitting the production of polypeptides which are useful as standards or reagents in diagnostic tests and/or as components of vaccines. Monoclonal antibodies directed against epitopes of the 15 kD OMP are also useful for diagnostic tests and as therapeutic agents for passive immunization.

FIG. 5

**DNA ENCODING THE 15 KD OUTER
MEMBRANE PROTEIN OF HAEMOPHILUS
INFLUENZAE**

Matter enclosed in heavy brackets [ ] appears in the original patent but forms no part of this reissue specification; matter printed in italics indicates the additions made by reissue.

BACKGROUND OF THE INVENTION

1. Field of the Invention

This invention relates to the 15 kD outer membrane protein of *Haemophilus influenzae* type b and nontypable *Haemophilus influenzae*.

For the sake of simplicity, *Haemophilus influenzae* is hereinafter referred to as *H. influenzae*.

sidered as components in the next generation of vaccines designed to prevent both serotype b and nontypable *Haemophilus* disease.

The object of the invention is to clone the gene for this *H. influenzae* protein, and to determine the DNA sequence thereof.

Accordingly, the present invention relates to a recombinant polynucleotide comprising a nucleotide sequence for the 15 kD protein of *Haemophilus influenzae* type b and nontypable *Haemophilus influenzae*, said protein having the amino acid sequence as follows:

2. Discussion of the Prior Art

Haemophilus influenzae type b is a major cause of meningitis and other invasive bacterial diseases in children under the age of five. Efficacious vaccines have been produced. The vaccines contain the type b capsular polysaccharide conjugated to a carrier protein. Nontypable *H. influenzae* cause surface mucosal infections in children and adults. Such organisms also cause invasive disease in children in the developing world and immunocompromised patients. The vaccines which have been developed to prevent disease due to type b organisms are not effective against nontypable *H. influenzae*.

SUMMARY OF THE INVENTION

Outer membrane proteins elicit antibodies which are protective in animal models and therefore should be con-

**Nucleotide Sequence Coding for a Common Outer
Membrane Protein from *H. influenzae* and
Monoclonal Antibodies**

55 The 15 kD outer membrane protein described herein is conserved among type b and nontypable *H. influenzae*. Epitopes on the native protein are recognized by the murine monoclonal antibodies 6B11, 1A6, and 5E6. The epitopes are present on the surface of intact *H. influenzae* cells. The gene for the 15 kD protein has been cloned and the DNA sequence thereof has been determined. The gene, when expressed in an appropriate host/vector system, produces a recombinant protein which is reactive with the monoclonal antibodies. Since the protein is antigenically highly conserved, it should receive serious consideration for inclusion in a vaccine to prevent *H. influenzae* disease. Moreover monoclonal antibodies and DNA probes may be used as a diagnostic tool to detect the presence of *H. influenzae*.

BRIEF DESCRIPTION OF THE DRAWINGS

FIG. 1 is a Western blot analysis of *H. influenzae* with monoclonal antibodies;

FIG. 2 is a partial restriction map of plasmid pRSM1255 which contains the gene for the 15 kD outer membrane protein from *H. influenzae* type b strain 1613;

FIG. 3 is a Western blot analysis of the expression of the recombinant 15 kD protein;

FIG. 4 is a dot blot immunoassay of extracts of *E. coli* strains LE392/pGD103 and LE392/pRSM1311; and

FIG. 5 is the amino acid sequence for the polynucleotide of the present invention. (SEQ ID NOS 1 and 2 are set forth in this Figure.)

DESCRIPTION OF THE PREFERRED EMBODIMENT GENERATION OF MONOClonAL ANTIBODIES

Monoclonal antibodies (Mabs) were obtained from two independent fusion experiments. Mab 1A6 was generated from Balb/c mice immunized with sarcosyl-insoluble proteins of nontypable *H. influenzae* MTL6 as described by Hamel et al [see Journal of General Microbiology (1992), 138, 161-168] and monoclonal antibodies 6B11 and 5E6, 25 were produced from mice immunized with outer membranes extracted from nontypable *H. influenzae* 12085 by the lithium chloride method described by Hamel et al [see J. Med. Microbiology, (1987) 23 163-170]. Isotype analysis revealed that the 1A6, 6B11 and 5E6 hybridomas secreted 30 immunoglobulin IgG2a, IgG1 and IgG3 respectively.

Referring to FIG. 1, Western Immunoblotting analysis of outer membrane preparations was performed. Outer membrane preparations were fractionated on 16% SDS-PAGE, transferred to nitrocellulose, and probed with Mab 1A6 (lane 1), 6B11 (lane 2), 5E6 (lane 3) and porin-specific Mab P2-18 (lane 4). The analysis indicated that the monoclonal antibodies were directed against a protein with an apparent mass of 15 kD. Antibody accessibility radioimmunoassay [see Proulx et al, Infection and Immunity (1991) 59, 963-970] indicated that monoclonal antibodies bound to surface-exposed epitopes on both type b and nontypable *H. influenzae* isolates.

CONSERVATION OF 15 KD-EPITOPES

A total of 193 *H. influenzae* isolates were tested by dot blot immunoassay for their reactivity with monoclonal antibodies 1A6, 6B11 and 5E6.

MOLECULAR CLONING OF THE GENE FOR THE 15 KD OUTER MEMBRANE PROTEIN

A lambda EMBL3 genomic library of DNA from *H. influenzae* strain 1613 was immunologically screened with murine monoclonal antibody 6B11 as described by Munson and Grass [see Infection and Immunity (1988) 561 2235-2242]. An immunologically reactive clone was isolated by plaque purification. A liquid lysate was prepared and DNA was purified from a Promega lambda DNA kit according to the manufacturer's directions. The *Haemophilus* insert was identified as a *Sall* fragment of approximately 16 kb. DNA from the lambda clone was partially digested with *Sau3A* and fragments of approximately 3-6 kb were isolated by preparative agarose gel electrophoresis. The 3-6 kb fragments were ligated into the low copy number vector pGD103 [see Deich et al, Journal of Bacteriology (1988) 489-498] which had been digested sequentially with *BamHI* and alkaline phosphatase. The ligation mixture was transformed into *E. coli* strain LE392 and the cells were plated on LB agar containing 35 µg/ml of kanamycin. Immunologically reactive colonies were identified by screening with murine Mab 6B11. Strain LE392/pRSM1255

was saved for further study. As shown in FIG. 2 plasmid pRSM1255 has an insert of approximately 3.8 kb. Strain LE392/pRSM1255 produces the full size protein as determined by Western blot (see FIG. 3). Membrane preparations were fractionated by SDS-PAGE, transferred to nitrocellulose and probed with murine monoclonal antibody 6B11. Lane 1 is the total membrane preparation of *H. influenzae* strain 1613; lane 2 is the total membrane preparation of *E. coli* strain LE392/pGD103 and lane 3 is the total membrane preparation of *E. coli* strain LE392/pRSM1255. The full size 15 Kd protein is produced by *E. coli* strain LE392/pRSM1255.

In order to further subclone the gene for sequencing, pRSM1255 was partially digested with Sau3A, fragments of approximately 0.5 to 1.5 kb were isolated, ligated into BamHI-treated pGD103 and transformed into *E. coli* strain LE392. An immunologically positive clone, designated

369 codon open reading frame (*SEQ ID NO:3*) was identified encoding a protein composed of 123 amino acids (*SEQ ID NO:2*) and having a molecular weight of 13,460. The open reading frame is notable for a lysine at position 3 and a cysteine at position 26 suggesting that the protein is a lipoprotein with a 25 amino acid leader peptide. (*The sequence of the protein without the leader peptide is set forth in *SEQ ID NO:4*.*)

10

DNA and protein sequence analysis were done using Gen Bank (a trademark of NIH) and EMBL (from European Molecular Biology Organization) data bases. The nucleotide (*SEQ ID NO:1*) and derived amino acid sequence (*SEQ ID NO:2*) of the 15 kD outer membrane protein of *H. influenzae* type b, strain 1613 is set out in Table 3.

LE392/pRSM1311 was saved for further analysis. Western blot analysis employing Mab 6B11 indicated that the full size protein was produced by this strain (data not shown). The Haemophilus insert in pRSM1311 is approximately 0.6 kb in size. Extracts of *E. coli* strain LE392/pRSM1311 react with all three murine Mabs (FIG. 4). 5 μ g of cell extracts were applied to the nitrocellulose and probed with Mabs 3B11, 1A6, and 5E6.

SEQUENCE ANALYSIS

The insert was cloned into M13mp18 and M13mp19 as a Sall to EcoRI fragment and sequenced in both directions. A

55

The sequence was found to have no significant homology to any known proteins including two previously described *Haemophilus* outer membrane lipoproteins of similar size.

60

The research described herein was supported in part by United States Public Health Service grant R01AI17572 from the National Institutes of Health.

(2) INFORMATION FOR SEQ ID NO:2:

(i) SEQUENCE CHARACTERISTICS:

- (A) LENGTH: 123 amino acids
- (B) TYPE: amino acid
- (C) STRANDEDNESS:
- (D) TOPOLOGY: linear

(ii) MOLECULE TYPE: protein

(xi) SEQUENCE DESCRIPTION: SEQ ID NO:2:

Met Thr Lys Ser Ser Ala Gln Ile Ala Glu Met Gln Thr Leu Pro Thr
 1 5 10 15

Ile Thr Asp Lys Thr Val Val Tyr Ser Cys Asn Lys Gln Thr Val Thr
 20 25 30

25 encoding a polypeptide comprising immunoreactive epitopes of the 15 kD outer membrane protein of Haemophilus influenzae.]

[2. A vector comprising a recombinant polynucleotide, wherein the recombinant polynucleotide is the recombinant polynucleotide of claim 1.]

[3. A host cell transformed with the vector of claim 2.]

[4. A recombinant expression system comprising a polynucleotide encoding a polypeptide comprising one or more immunoreactive epitopes of the 15 kD outer membrane protein of claim 1, wherein the polynucleotide is operably linked to a control sequence compatible with a desired host.]

[5. A cell transformed with a recombinant expression system, wherein the expression system is the recombinant expression system of claim 4.]

40 6. A recombinant polynucleotide encoding a polypeptide comprising the amino acid sequence of SEQ ID NO:2.

7. The recombinant polynucleotide of claim 6, comprising the nucleotide sequence of SEQ ID NO:3.

8. A recombinant polynucleotide encoding a polypeptide comprising the amino acid sequence of SEQ ID NO:4.

9. A recombinant vector comprising a recombinant polynucleotide encoding a polypeptide comprising the amino acid sequence of SEQ ID NO:2.

10. The recombinant vector of claim 9, wherein the recombinant polynucleotide comprises the nucleotide sequence of SEQ ID NO:3.

11. A recombinant vector comprising a recombinant polynucleotide encoding a polypeptide comprising the amino acid sequence of SEQ ID NO:4.

12. A host cell transformed with a vector comprising a recombinant polynucleotide encoding a polypeptide comprising the amino acid sequence of SEQ ID NO:2.

13. The host cell of claim 12, wherein the recombinant polynucleotide comprises the nucleotide sequence of SEQ ID NO:3.

14. A host cell transformed with a vector comprising a recombinant polynucleotide encoding a polypeptide comprising the amino acid sequence of SEQ ID NO:4.

15. A recombinant expression system comprising a recombinant polynucleotide encoding a polypeptide comprising the amino acid sequence of SEQ ID NO:2 operably linked to a control sequence compatible with a desired host.

17

16. *The recombinant expression system of claim 15, wherein the recombinant polynucleotide comprises the nucleotide sequence of SEQ ID NO:3.*

17. *A recombinant expression system comprising a recombinant polynucleotide encoding a polypeptide comprising the amino acid sequence of SEQ ID NO:4 operably linked to a control sequence compatible with a desired host.*

18. *A cell transformed with a recombinant polynucleotide encoding a polypeptide comprising the amino acid sequence of SEQ ID NO:2.*

19. *The cell of claim 18, wherein the recombinant polynucleotide comprises the nucleotide sequence of SEQ ID NO:3.*

20. *A cell transformed with a recombinant polynucleotide encoding a polypeptide comprising the amino acid sequence of SEQ ID NO:4.*

21. *A method of making a recombinant vector capable of expressing a polypeptide comprising the amino acid sequence of SEQ ID NO:2, comprising*

inserting a recombinant polynucleotide encoding a polypeptide comprising the amino acid sequence of SEQ ID NO:2 into a plasmid.

22. *The method of claim 21, wherein the polynucleotide comprises the nucleotide sequence of SEQ ID NO:3.*

23. *A method of making a recombinant vector capable of expressing a polypeptide comprising the amino acid sequence of SEQ ID NO:4, comprising*

18

inserting a recombinant polynucleotide encoding a polypeptide comprising the amino acid sequence of SEQ ID NO:4 into a plasmid.

24. *A method of making a polypeptide comprising the amino acid sequence of SEQ ID NO:2, comprising*

culturing a host cell transformed with a recombinant vector comprising a recombinant polynucleotide encoding a polypeptide comprising the amino acid sequence of SEQ ID NO:2, whereby the host cell expresses the polypeptide, and

isolating the polypeptide.

25. *The method of claim 24, wherein the polynucleotide comprises the nucleotide sequence of SEQ ID NO:3.*

26. *A method of making a polypeptide comprising the amino acid sequence of SEQ ID NO:4, comprising*

culturing a host cell transformed with a recombinant vector comprising a recombinant polynucleotide encoding a polypeptide comprising the amino acid sequence of SEQ ID NO:4, whereby the host cell expresses the polypeptide, and

isolating the polypeptide.
